date Feb. 10. 1836.

Letter'd Patents Received - Re-

corded again

The schedule referred to in these Letters Patent and
making part of the same, containing a description in the words
of the said Joseph Girard himself of his improvement in the
Machine for cutting stone and other substances.

To all to whom these presents shall come: Be it known
that J. Joseph Girard, an alien resident two years, U. S. born
in the United States, of Geneva in the County of Ontario and
State of New York, has invented a new and useful im-
provement in a stone cutting machine and that
the following is a full and exact description of the construction
and operation of the said machine as invented or improved
by me: The machine has a vertical revolving motion and
may be propelled by man, horse, team or other power
and with the ease by which it may be used and put into
operation, has a decided advantage over any other stone
cutter known to the said Girard. The plates hereto annexed
1. & 2. and the lettering of the same together with the specifica-
tion of the machine given below, will particularly describe
and describe the different parts of the machine, the distinct
operation of each part and the effect produced by com-
bining the whole with respect to use to with Plate 3, letter
A. represents an upright and view of the frame, flywheel,
tines, finger wheels, worm wheel and pieces when the
machine is in the operation of cutting. Plate A. 2 letter
B. represents an upright right side view of the frame,
flywheel, finger wheels and prop. Plate A. 3 letter C.
represents an upright left side view of the frame, fly
wheel, worm wheel, worm spindle and prop. - Plate A.
letter

letter A. b. b. represents the legs of the frame. a the cross
 ledge connecting and supporting the two legs b. b. c. re-
 presents the face of the machine into and supporting
 the legs b. b. at top. d. the rim of the fly wheel e. e. the arms
 of the fly wheel of the machine forming a. a. a. a. f. the bolts
 connecting the knives to the arms of the fly wheel as
 will more plainly appear in plates Nos 3 & 3. f. repre-
 sent the knives of concave edges bolted onto the
 arms of the fly wheel e. e. which may be increased
 to six knives or reduced to one knife. h. represents
 the handle attached to the fly wheel for the purpose
 of propelling the machine by manual power as will
 plainly appear by plates Nos. 3 & 3. h. h. represent two
 flat end rollers for the purpose of drawing the straw
 forward on the journals of which are attached finger
 wheels 1. 1. as will more plainly appear in plate No
 3. 3. 3. which are propelled by worm wheel 77. as will
 plainly appear in plate 3. 3. 3. 3. represent the top part of
 the prop. which passes the straw after it leaves the
 rollers. the unshaded part letter k represents the space
 where the straw passes through to be cut by the knives.
 3. 3. represents the lower part of the press frame in
 supporting at the top roller k. which rises and falls
 to receive and press the straw of any thickness within
 the description of the finger wheel. by means of lever
 3 and weight 3. as will plainly appear in plates Nos 3 & 3.
 3. represents the mode of connecting the lower part of the press
 frame with the lever 3. 3. represents the box of the cou-
 pling of the worm spindle to the fly wheel d. Plate 3. 3. letter
 B. b. b. represent the legs of the right side of the frame. a.
 represents the right side ledge connecting and supporting
 the legs of the frame. c. represents the right side of the box
 in which the straw is placed similar to the box of

the

The common straw cutter. A represents the upright edge of the fly wheel. B.B.B.B.B.B.B. represent the bolts fastening the knives to the arms C.C. as described in plate N°. 1. E represents the handle by which the fly wheel is propelled by manual power. D.D. represent the double finger wheels which may rise and fall, from the center, from one inch to a foot if required and still work perfectly smooth. Journals of which are placed the rollers in E.E. as described in plate N°. 1 which rollers will rise and fall to admit straw or any other fodder of any thickness without the description of the finger wheels the top roller being pressed by the lever 8, and weight 9, attached by the lower part of the head frame 9 A. G. G. represents the screw used to support the brace H. Plate N°. 3. Lever C. represents an upright left view of the machine. - B.B.A.B.B.B.B.B.B.B.B. represent the screws described in plate N°. 2. E represents the iron and spindle mashing into the edge of worm wheel B.B.B.B. which is placed the fly wheel A which fasts the rollers, knives and all in motion. A represents the center screw to the spindle D by which the knives may be drawn closer and regulated with the use of the hand lever. G represents a brace supporting the coupling of the spindle D and the center screw H. G. the screw used to support the brace H. on the coupling for the removal of spindle D.

The petitioners claim an exclusive right to the invention of the finger wheels, the rising and falling of the rollers, the compression produced by the screw S. & weight, the concavity of the knives edge, the plan of the face of the machine through which the straw is drawn; the center screw on the worm and spindle and its use.
